(57) **CLAIM**

The ornamental design for an earphones charging case, as shown and described.

DESCRIPTION

FIG. 1 is a top front perspective view of an earphones charging case showing my design;

FIG. 2 is a bottom rear perspective view of the earphones charging case showing my design;

FIG. 3 is a front elevation view of the earphones charging case of FIG. 1;

FIG. 4 is a rear elevation view of the earphones charging case of FIG. 1;

FIG. 5 is a left side elevation view of the earphones charging case of FIG. 1;

FIG. 6 is a right side elevation view of the earphones charging case of FIG. 1;

FIG. 7 is a top plan view of the earphones charging case of FIG. 1; and,

FIG. 8 is a bottom plan view of the earphones charging case of FIG. 1.

The broken lines in the drawings are for illustrating unclaimed portions of the earphones charging case, and form no part of the claimed design.

1 Claim, 8 Drawing Sheets
